WITNESS:

BY *Victor J. Evans* ATTORNEY

ATTORNEY

UNITED STATES PATENT OFFICE.

MONROE HUGGENS, OF COOKVILLE, TENNESSEE.

CULTIVATOR STRUCTURE.

Application filed December 14, 1921. Serial No. 522,270.

To all whom it may concern:

Be it known that I, MONROE HUGGENS, a citizen of the United States, residing at Cookville, in the county of Putnam and State of Tennessee, have invented new and useful Improvements in Cultivator Structures, of which the following is a specification.

My present invention is designed more particularly as an improvement on the construction disclosed in my contemporary application filed June 15, 1920, Serial No. 389,169.

The general object of the present invention is the provision of an improved and highly efficient cultivator construction.

To the attainment of the foregoing, the invention consists in the improvement as hereinafter described and definitely claimed.

In the accompanying drawings, forming part of this specification:—

Figure 1 is a view showing a wheeled structure embodying my invention with the near ground wheel omitted and the spindle therefor in section.

Figure 2 is a plan view showing said structure complete.

Figure 3 is a detail front elevation with parts in transverse section.

Figure 4 is a detail side elevation of one of my novel planter units.

Similar numerals designate corresponding parts in all of the views of the drawings.

The wheeled structure illustrated comprises a main frame 1, an axle 2 and ground wheels 3. The main frame 1 is of general U-shape in plan, with the bight of the loop foremost and the ends thereof connected to the axle, it being understood in this connection that the main frame is arranged forward of the axle. The said main frame 1 includes upper and lower bars 4, Figures 1 and 3, bolts 5 connecting the same, and tubular sections 6 mounted on the bolts 5 and interposed between the bars 4 and having for their function to brace the bars and to maintain the same in spaced relation. The axle 2 includes a horizontal intermediate portion, pendent portions integral with the ends of the intermediate portion and spindles extending outwardly from the said pendent portions, the ground wheels 3 being mounted on the said spindles in the ordinary well known manner.

The structure also includes a tongue 7, and a double-tree 8 connected to the tongue

in front of the main frame 1. At an intermediate point of its length the tongue is pivotally connected to the forward portion of the main frame 1, a clip 10 being disposed over the tongue and a pivot bolt 11 being extended through the clip 10, the tongue 7 and the forward portion of the main frame 1. The rear end of the tongue 7 is equipped with a rearwardly extending metallic bar 12, Figure 2, which is adapted to play between two transverse straps 13 that are fixed to the main frame 1 and constitute a race for the bar 12 when the rear portion of the tongue is moved in either direction.

At 15 is a driver's seat, and at 16 the support therefor, said support being connected at 15^x to the axle 2, and at 16^x, Figure 1, to the forward portion of the frame 1.

Appropriately fixed with respect to and arranged transversely of the forward portion of the main frame 1 is a tubular member 31. The said transverse tubular member 31 preferably extends between the bars 4 of the main frame, and is disposed and held in shackles 32, each of which has its arms connected to the frame 1 through the medium of a bolt 33 that extends through the upper and lower bars 4 and the arms of the shackles as shown. Telescopically journaled in the tubular member 31, and detachably retained by keys 34 are inwardly-directed arms 34^x on beams 25^a, there being one beam 25^a to each of the planter units, and each key 34 being movable in an arcuate slot 34^e in the transverse member 31.

At 37 is an arch member for unit-holding and spacing purposes. The said arch member is provided with end portions 37^x in each of which is a plurality of apertures for adjustment purposes, and on each of which is an upstanding rod 38^x which carries a spring 38.

The structure also includes levers 39 for the raising and lowering and adjustable fixing of the arch 37. The said levers shown as hand levers extend upwardly from the rear portions 1^x of the frame 1, and their lower portions 39^x extend forwardly to the rods 38^x to which they are connected.

Each of the before mentioned beams 25^a is fixed to or integral with a sub-beam 25^b extending rearwardly from the lower end of the beam 25^a. Said sub-beam 25^b is connected at 25^c to one end portion of the arch

37, and carries a furrow-forming disk or other ground working device 50, a seed box 51, a fertilizer box 52, a combined covering and traction wheel 53, and the usual or any 5 other appropriate mechanism operable by said wheel 53 to discharge seed from box 51 and fertilizer from the box 52. By placing the planter beams 25^a equipped as described in the wheeled structure and connecting the arch member 37 to the beams 25^b, it will be manifest that the structure will be converted into a two-row planter, it being understood in this connection that the planter mechanism of the two units are 15 of the right and left hand type, respectively. Manifestly the planter mechanisms may be made comparatively light and the springs 38 may be depended upon to hold the two planter units to their work. It will also 20 be manifest that when desired the machine may be expeditiously and easily reconverted from a planter into a cultivator in the manner fully set forth in my said contemporary application.

25 As best shown in Figures 1 and 4 the ground working or furrow-forming device 50 of each of the units is carried on the rear portion of a beam 65, pivotally connected at 66 to the beam 25^b. The said beam 65 is provided with a pendent arm 67 having a plurality of apertures for adjustment purposes, and connected to the said arm 67 is a link 68, arranged to play through a guide 69 on the beam 25^b and connected to the lower end of a lever 70, the upper end of which is pivotally connected at 71 with the doubletree 8. Connected to the said lever 70 adjacent to the center thereof is a singletree 72 adapted 30 for the connection of a draft animal in the ordinary or any other desired manner. Manifestly the draft animal pulling on the lever 70 will serve to hold the ground working device or furrow-former 50 down to its work and will similarly hold the wheel 53 down to its work. As shown in Figures 1 and 4 the rear arm of the beam 65 in each planter unit is arranged and adapted 35 to move to a limited extent in a hanger 73 on the beam 25^b. This provision permits of the upward movement of the beam 65 relative to the beam 25^b, this being advantageous inasmuch as it enables the device 50 to rise and pass over or clear an obstruction in its path without raising of the adjacent covering and traction wheel 53.

40 In order to yieldingly and adjustably hold the furrow-forming or ground working device 50 of each unit down to its work I provide in each unit a lever 74. The said lever is equipped with a detent 75 to engage a rack 76 fixed on the beam 25^b and is also provided with a rearwardly directed arm 77. Connected to the said arm 77 and

extending downwardly and loosely through the beam 65 is a rod 78 on which is a spring 79, said spring 79 being interposed between the lever arm 77 and the beam 65 so as to tend to press the said beam 65 downwardly. Manifestly the spring 79 will yield and permit of upward movement of the beam 65 in the contingency before referred to.

I have entered into a detailed description 75 of the construction and relative arrangement of the parts embraced in the present and preferred embodiment of my invention in order to impart a full, clear and exact understanding of the said embodiment. I 80 do not desire, however, to be understood as confining myself to the said specific construction and relative arrangement of parts inasmuch as in the future practice of the invention, various changes and modifications may be made such as fall within the scope of my invention as defined in my appended claims.

Having described my invention, what I claim and desire to secure by Letters-Patent, is:—

1. The combination in a wheeled agricultural apparatus, of an axle having an intermediate portion and pendent end portions, and spindles on said pendent portions, a main frame connected to said axle, a transverse member carried by the forward portion of the frame, trailing beams connected with the end portions of said transverse member, a transverse arch member connected to said beams and having upwardly extending rods, levers mounted on the frame and having arms connected to said rods, springs mounted on said rods and interposed between the arch member and said lever arms, draft means connected with the frame, beams pivoted at their forward ends to the trailing beams and extending rearwardly from the points of connection and having on their rear portions ground-working devices and also having arms at their forward ends, and connections between said arms and said draft means.

2. The combination in a wheeled agricultural apparatus, of an axle having an intermediate portion and pendent end portions, and spindles on said pendent portions, a main frame connected to said axle, a transverse member carried by the forward portion of the frame, trailing beams connected with the end portions of said transverse member, a transverse arch member connected to said beams and having upwardly extending rods, levers mounted on the frame and having arms connected to said rods, springs mounted on said rods and interposed between the arch member and said lever arms, draft means connected with the frame, beams pivoted at their forward ends to the trailing beams and extending rear- 125 130 135 140 145 150 155 160 165 170 175 180

- wardly from the points of connection and having on their rear portions ground-working devices and also having arms at their forward ends, connections between said 5 arms and said draft means, levers on the trailing beams and having arms, rods connected to said arms and extending loosely through the beams carrying the ground-working device, springs on said rods between said beams and the lever arms, and 10 means to adjustably fix said levers with respect to said trailing beams.
3. A unit for use on wheeled agricultural apparatus, comprising a pendent beam for 15 connection to the frame of such apparatus, a trailing beam carried by and extending rearwardly from said pendent beam, a beam pivotally connected to said trailing beam and extending rearwardly and downwardly from 20 said point of connection and having a ground working device on its rear portion and an arm at its forward end, a lever on the trailing beam, means to adjustably fix said lever with respect to said beam, a rod 25 connected with the lever and extending through the beam carrying the ground working device, and a spring on said rod and between said beam and said lever.
4. The combination in an agricultural apparatus of a wheeled frame, draft means 30
- connected with said frame, trailing beams connected with said frame, beams pivotally connected with the trailing beams and extending rearwardly and downwardly from 35 said points of connection and equipped on their rear portions with ground-working devices and having at their forward ends arms, and connections intermediate said arms of 40 said beams and the said draft means.
5. The combination in an agricultural apparatus of a wheeled frame, draft means connected with said frame, trailing beams connected with said frame, beams pivotally connected with the trailing beams and extending rearwardly and downwardly from 45 said points of connection and equipped on their rear portions with ground working devices and having at their forward ends arms, and connections intermediate said arms of 50 said beams and the said draft means; the said trailing beams being equipped with levers and means to adjustably fix said levers with respect to said beams, and yielding means being interposed between the 55 beams carrying the ground working devices and the said levers.

In testimony whereof I affix my signature.

MONROE HUDGENS.
